UNITED STATES PATENT OFFICE.

FREDERICK N. WOLF, OF ST. LOUIS, MISSOURI.

TEMPORARY BINDER.

No. 806,861.

Specification of Letters Patent.

Patented Dec. 12, 1905.

Application filed March 13, 1905. Serial No. 249,863.

To all whom it may concern:

Be it known that I, FREDERICK N. WOLF, a citizen of the United States, and a resident of the city of St. Louis, State of Missouri, have invented certain new and useful Improvements in Temporary Binders, of which the following is a specification containing a full, clear, and exact description, reference being had to the accompanying drawings, forming a part hereof.

My invention relates to temporary binders; and it consists of the novel features herein shown, described, and claimed.

The object of my invention is to provide improved temporary binders especially for use in connection with magazines and telephone-directories and which shall possess superior efficiency and simplicity.

In the drawings, Figure 1 is a plan view of my invention attached to the tubular metallic face. Fig. 2 is a sectional side elevation of same. Fig. 3 is an enlarged perspective view of the detachable prong and ring carrier. Fig. 4 is an end view of the tubular base, the prong and ring carriers being detached therefrom. Fig. 5 is a sectional end elevation showing my invention in proper position with relation to the binder-covers, the section through the tubular base being taken on the line 10 10 of Fig. 1.

1 indicates the tubular base, which is preferably flattened, as shown, and composed of sheet metal, and the same has length corresponding to the length of the magazine to be bound, and said base is adapted to be secured centrally between the two covers 2 and secured in position by means of double fabric 3, pasted over the same.

The principal portion of my invention resides in the combined prong and ring carriers. (Shown more clearly in Fig. 3.)

I provide a carrier at each end of said base 1. Said carriers are formed of a single piece of metal bent at the center of its length to form the ring and having its two arms extending parallel and doubled upon and into contact with themselves for a distance to form the opposite spring-arms 5, with an eye 6 at their free ends, and projecting upwardly and inwardly from the base of said spring-arms 5 are a pair of prongs 7, which are to be inserted between the leaves of the magazine in order to hold the same in the binder.

The base 1 at the end (shown at the right

hand of Figs. 1 and 2 and which I term the 55 "lower end") is provided with an integral book-supporting flange 8, which projects at right angles and upon which the end of the book or magazine is adapted to rest when the binder containing the book is hung up by 60 means of the ring 4 at the opposite end.

The yielding arms 5 of the carriers are inserted in the base 1, and those at what I term the "upper end" of the base are permanently secured by two punch depressions 9, made in 65 the upper surface of the base directly over the eyes 6 and in such manner that the metal of the base is driven downwardly and forms a projection within said eyes 6.

The carrier at the lower end of the base is 70 detachably held within the base by making a punch depression 10 in the top of said base in such manner that the metal will be projected downwardly, as shown in Fig. 5, and engages the inner opposite edges of said eyes 6. 75

The operation is as follows: When it is desired to place a book or magazine in the binder, it will only be necessary to detach the lower carrier from the base 1, then place the book upon the said base and insert the 80 prongs 7 of the upper carrier between the leaves of the book, which will secure the upper end of the book in position, after which the lower end of the book should be secured by inserting the prongs 7 of the lower carrier 85 between the leaves of the book and also inserting the yielding arms 5 of the lower carrier into the end of said base and pushing same upwardly until the eye 6 passes the center of the punch depression 10, which latter will retain said arms in position by reason of frictional contact. When it is desired to detach the book from the binder, the same can be accomplished very quickly by grasping the ring 4 of said lower carrier and jerking the carrier out of said base, thereby detaching the prongs of the carrier from the book and releasing the same. 95

It will be observed that the yielding arms 5 of the lower carrier are normally spread 100 apart a greater distance at their free ends than at their bases, as clearly shown in Fig. 3, so that when said arms are inserted in the base they will be urged apart and into frictional contact with the edges of the base by 105 reason of the inherent yielding force of the integral ring 4.

If desired, I may make the carriers out of

sheet metal by stamping them from an integral sheet into approximately the form shown in Fig. 3.

What I claim is—

- 5 1. The improved temporary binder, comprising the integral combined prong and ring carriers made of a single piece of metal bent to form yielding arms, and a suitable tubular base within which said arms are inserted; and
- 10 10 projections extending from said base and engaging the yielding arms of said carriers to retain them in position; substantially as specified.
- 15 2. The improved temporary binder, comprising the integral combined prong and ring carrier made of a single piece of metal bent

to form yielding arms, and a suitable tubular base within which said arms are inserted; and projections extending from said base and engaging the yielding arms of said carriers to retain them in position; and the book-supporting flange 8 projecting from said base at the lower end thereof; substantially as specified.

In testimony whereof I have signed my name to this specification in presence of two subscribing witnesses.

FREDERICK N. WOLF.
